CARD STENCIL

Harmon P. Elliott, Watertown, Mass., assignor to
 The Elliott Addressing Machine Company, a
 corporation of Massachusetts

Application August 3, 1939, Serial No. 288,127

8 Claims. (Cl. 101—127)

This invention consists in a small but very useful improvement on the type of card stencils and blanks for making same which have been marketed for many years in connection with addressing machines to form therewith a species of printing apparatus, and it embodies a successful solution of a long standing difficulty often encountered during the operation of such apparatus.

10 The well known general features of construction of such card stencils comprise a rectangular frame composed of two sections of cardboard or similar stiff paper fabric superposed with their outer edges in registry one with another, a welt strip of thinner but tough, flexible material cemented between said cardboard sections but having its inner edge portions projecting slightly beyond their inner edges, and a panel of properly coated Yoshino paper having its marginal portions overlapping and cemented to said projecting edge portions of said welt strip.

The outside dimension of such card stencils have not varied since the beginning of the business in such apparatus, and cannot safely be changed because they must fit into the guides and magazines of any one of the thousands of machines now in the hands of purchasers of such stencils. Also the stencilizable area of each has been standardized to conform to the standardized ink applying mechanism of such machines.

As a result of such limitations and certain preconceived ideas as to certain other requirements, a relatively wide portion of the welt strip along the frame at each end of the card has been allowed to project inwardly therefrom and so be left free to crinkle or buckle when expanded by the absorption of moisture or other cause in a manner illustrated (with a little exaggeration) in Fig. 6 of the accompanying drawing, and whenever any of the crests of the welt convolutions so formed approach or extend beyond the plane of the adjacent surface of the stencil frame they are liable to catch on the inner edge of the end portion of the frame of the next stencil in the magazine stack when the bottom one is being slid out of such stack preparatory to its passage to the printing zone. Any such interlocking action is liable to partially disrupt one or the other of the stencils involved, or to jam them together in the discharge slot of the magazine.

Also such crests of the welt waves often rub on the inked panel face of the next stencil, while one of them is being pushed out of the magazine, and the ink so picked up is offset later on the face of any envelope or sheet of paper which

is being addressed by said first mentioned stencil, thereby producing an unsightly smudge.

The above described unsupported condition of the welt strip at each panel end has resulted from the end portions of the lower or back section of the cardboard frame (meaning the back section when one is reading the stencil) being made narrower than the side portions thereof, as shown in Fig. 5 in said drawing, and the essence of my present invention consists in the discovery that such narrow construction of end sections is not necessary, as heretofore supposed, but that, on the contrary, making them of substantially the same width as the side sections not only produces a stronger stencil but, most important of all, permits cementing the welt sections extending across the ends so firmly to the frame sections then underlying them, that all the obnoxious crinkling or buckling of such welt section is thereby prevented.

The best embodiment of my present invention now known to me, together with an illustration of the defect in prior art forms which it is designed to correct, are shown in the accompanying sheet of drawings in which,

Fig. 1 is an enlarged front view of such improved stencil.

Fig. 2 is a back view with the stencil turned upside down.

Fig. 3 is a longitudinal section on line 3—3 of Fig. 1 on an enlarged scale and looking in the direction of the arrows, with parts broken away.

Fig. 4 is a cross section on line 4—4 of Fig. 1 on an enlarged scale with parts broken away.

Fig. 5 is a fragmentary back view on a smaller scale of one end of a prior art stencil, and

Fig. 6 is a cross section on line 6—6 of Fig. 5 drawn on a larger scale than Fig. 5, and looking in the direction of the arrows thereon, these two views illustrating the formerly occurring crinkled condition of one end section of the welt which can now be prevented by my present invention.

Throughout the drawing like reference characters indicate like parts. Referring to Figs. 1 to 4, the card frame indicated generally by P is composed of a front section 1 and a back or rear section 2, the designation "front" or "back" referring to the position assumed when the stencil is so held that any legend which has been cut in the panel P thereof can be read. As shown, each of said frame sections has a uniform width throughout except along the notch 5, but the back section 2 is about 50% wider than the front one so that it has an inner border portion 55

3 which projects beyond the corresponding border of front section 1.

W indicates the usual welt strip of tough, flexible material, the main portion of which is cemented between the adjacent, opposing surfaces of the frame sections 1 and 2, as heretofore, and the portions thereof which overlie the exposed border portion 3 of the back frame section 2 are cemented to it, there being also extremely narrow marginal portions 4 which project still further beyond the inner edges of said back frame section.

P indicates the usual panel of Yoshino paper having a coating which is displaceable laterally by type face pressure so as to expose some portions of the loosely felted Yoshino fibres and thereby render them permeable to ink. Also the marginal portions of said panel which overlie the exposed portions of the welt strip are cemented thereto in the usual way.

The above described construction produces a card-stencil or blank which has a frame of uniform cross section and consequent strength throughout, except along the short notched section before referred to. And, most important of all, such improved construction leaves no part of the welt strip, except the very narrow marginal section 4, free to expand to a greater extent than does the frame F and consequently wrinkle or crinkle as shown in Fig. 6.

As contradistinguished from the above, the prior art stencil of this general construction, shown in Figs. 5 and 6, has always had the end portions 6 of its back frame section 12 made as narrow as those of its front frame section 11, consequently leaving a wide marginal portion 7 of each end section of its welt strip unconfined except around three of its edges, so that it necessarily becomes wrinkled, as best shown at 40 8 (Fig. 6), whenever it is expanded by heat or by the absorption of moisture to a greater extent than the adjacent end portion of frame F is simultaneously expanded. The frame, being made of specially selected cardboard stock, absorbs but little moisture so that its coefficient of expansion under increases of humidity is relatively low. The best material for use in forming the welt strip, however, has the drawback of a much higher coefficient of expansion under 50 similar conditions, and such swelling is especially developed in the direction crossways of the web thereof which comes from the paper machine in which it is manufactured. And as these stencil blanks have all been stamped out of strips formed 55 as indicated generally in Patent No. 1,034,600 to Sterling Elliott granted Aug. 6, 1912, and on machines of the type shown in the later Patent No. 1,121,080 granted to him Dec. 15, 1914, the "grain" of the welt strip (i. e. the predominating 60 direction of the fibres composing it) must run lengthwise of each such completed stencil, and the maximum expansion of such welt strip on absorption of moisture which always develops transversely of its grain will then occur along 65 lines running transversely of the stencil. Consequently the resultant crinkled condition shown in Fig. 6 has heretofore been practically unavoidable. And when that deformation of the parts has developed to a degree such that the 70 crests of some of the welt convolutions extended beyond the plane of the adjacent face of the frame section 12, as shown at 9 in Fig. 6, the ends of such crests would catch on the inner edge of the end section of the frame of the next stencil in a stack (as before mentioned) when one was

slid past the other in feeding the bottom stencil out of the magazine to the printing zone. If the stencils were stacked face upward, as in most addressing machines of my design, the frame of the bottom stencil would catch on the wrinkled welt of the stencil next above it while being pushed out of the stack. And if the stencils were stacked face downward the wrinkled welt on such bottom stencil would catch on the frame of the one above it while being so discharged from the magazine. In either case the wave crests also became ink coated and offset that ink onto the envelopes or sheets of paper against which they were pressed in subsequent printing operations.

The present invention prevents such highly objectionable crinkling of the welt sections at the ends of the stencil card (1) by cementing their rear surfaces firmly to the underlying faces of the projecting portions of the back frame 2, 20 which will not buckle, and (2) by covering their front faces with the coated Yoshino paper of panel P and the film of cement by which the two are held together so that less moisture can get to the welt section sandwich so formed.

The form of stencil blank shown in Figs. 5 and 6 was adopted about 25 years ago as a result of evolution in commercial use after the forms shown in my Patent No. 1,068,578 dated July 29, 1913, and in Patent No. 1,480,200 granted to my father Sterling Elliott Jan. 5, 1924, had successively proved unsatisfactory in routine use, and has been continuously sold to users of addressing machines during all that time. The end section 6 of the back frame section was originally 35 made narrow as shown in Fig. 5 because of a mistaken notion we then had that it must not extend to a point near an end of the standard ink carrying roll of our machines, which has always been, and still is $3\frac{1}{2}$ or more inches long, while 40 the over-all length of our stencil is only $4\frac{1}{2}$ inches. To ensure this clearance, so supposed to be necessary,—the end sections of the back frame have heretofore been kept narrow, as shown in Fig. 5. This impression was a "carry-over" from 45 the troubles we had with stencils made as shown in the above mentioned Patent No. 1,480,200, the end portions of the back frame section of which came nearly under such roll ends, with the result that the Yoshino panel was cut along such 50 frame edges under repeated applications of roll pressure.

I have now discovered, however, that when the welt sections cemented to their under surfaces 55 and extending slightly beyond the cutting edges of the back frame section, as shown in Figs. 1 to 4, no such shearing action occurs and stencils made according to my present invention may be retained in use indefinitely.

I prefer to have the width of the welt marginal portion 4 from $\frac{1}{32}$ to $\frac{1}{16}$ inch wide and to have the stencilizable panel P overlap said welt strip about $\frac{1}{4}$ inch. That forms a durable flap construction which will bend around the underlying 65 edge of the back frame section without cracking.

As showing that the difficulty with the crinkling welt of the old form of stencil has for some time been realized in the art, I may refer to my Patent No. 2,145,300 dated Jan. 31, 1939, granted on an 70 application filed Jan. 31, 1938, which shows another, but only partially successful, attempt to eliminate it. The construction there shown also left weak spots in the end portions of the composite frame.

Also, elaborate and costly apparatus has been devised and employed in the stencil blank manufacture to ensure the frame and the welt strips being maintained under exactly the same moisture and heat conditions while in storage before being cemented together and while being so assembled, but after all that care in manufacture it is evident that the more hygroscopic, exposed welt section will swell more in a fog than will the adjacent frame section of relatively non-hygroscopic cardboard in which it is set, and that crinkling of the former must then occur if it is confined only along marginal portions thereof.

Having described my invention, I claim:

1. As a new article of manufacture a card stencil formed of a rectangular frame composed of two layers of cardboard, each of substantially uniform width throughout, with their outer edges superposed in registry one with another but having that layer which forms the back of the stencil, whenever it is in position such that any legend cut therein can be read, extending inwardly at all points a substantially uniform distance beyond the inner edges of the front frame layer so as to form a depressed border portion of substantially uniform width surrounding the panel opening in the composite frame, together with a tough, but flexible welt strip of substantially uniform width so cemented between said frame portions that only very narrow marginal portions thereof project into said panel opening, and a panel of stencilizable fabric lying within the opening of said front frame layer and cemented along all its border portions to the front face of said welt strip; whereby no portion of said welt strip wide enough to crinkle perceptibly on expansion is left exposed and free to crinkle.

2. An article of manufacture such as defined in claim 1 in which the opposite end portions of said back frame are made about 50% wider from their outer edges to their inner edges than said front frame at the same points.

3. An article of manufacture such as defined in claim 1 in which said welt margin extends from about $\frac{1}{32}$ to about $\frac{1}{16}$ of an inch beyond the inner end edges of said back frame.

4. As a new article of manufacture a card stencil having a rectangular frame composed of two superposed layers of cardboard and having the frame layer which forms the back of the stencil, when it is in position such that the legend cut therein can be read, projecting into the panel space beyond the inner edges of the other layer a uniform distance all the way around said panel space so as to form a depressed border portion of substantially uniform width surrounding the same; together with a welt strip of tough but flexible material so cemented between said frame

portions that only uniformly narrow marginal portions thereof project into said panel opening, and a panel of stencilizable material lying within the opening in said front frame layer and cemented along all its border portions to said welt and overlaying said back frame; whereby no portion of said welt strip wide enough to crinkle perceptibly on expansion is left exposed and free to crinkle. 5

5. An article of manufacture such as defined in claim 4 in which said back frame at all points is about 50% wider from its outer edge to its inner edge than said front frame.

6. An article of manufacture such as defined in claim 4 in which said welt margin extends from about $\frac{1}{32}$ to about $\frac{1}{16}$ of an inch beyond the inner end edges of said back frame.

7. As a new article of manufacture a card suitable for forming a type-cut stencil which has a rectangular frame composed of two sections of cardboard superposed with their outer edges in registry one with another, said sections each having a substantially uniform width throughout but one being wider than the other so that its inner edges extend beyond the inner edges of said other, 25 a welt strip of thinner but tough flexible material cemented between said cardboard sections and overlying and extending slightly beyond the inner end edges of the wider one, and a panel of stencilizable material covering the opening in the composite frame so formed and having its marginal portions overlapping and cemented to substantially all portions of said welt strip which project beyond the inner edges of said narrower frame section; whereby substantially all of both surfaces of said welt strip are confined between and firmly cemented to oppositely disposed surface portions of said frame and panel so that no crinkled edges thereof are left exposed. 30 35

8. As a new article of manufacture, a stencil consisting of a two-layer frame providing a panel opening, a windowed welt sheet positioned between and cemented to the adjacent surfaces of the frame layers and a stencilizable sheet adhesively attached to the marginal portion of the welt sheet around the window therein, the panel opening in one frame layer being smaller than the opening in the other layer, and the window in the welt sheet being so dimensioned as to lie within the smaller panel opening with the marginal portion of the welt sheet around the window therein overlapping the end edges of said smaller panel opening and serving as a protective covering to prevent cutting of the stencilizable sheet by said end edges under the squeeze of the printing roll when the stencil is in use.

HARMON P. ELLIOTT.
